DRAWING BOARD

Jack C. Pratt, Brooklyn Heights, N. Y.

Application March 9, 1945, Serial No. 581,735

5 Claims. (Cl. 45—131)

1

This invention relates to drawing boards, and more particularly to a drawing board of the readily portable type.

One object of the invention is to obviate the need of a considerable number and varied types of plane guiding instruments required for making a drawing on the board.

Another object is to facilitate the manipulation of such guiding instruments on and their removal from the board.

Still another object is to enable a work-sheet to be quickly and effectively secured to the board.

Other objects will be in part obvious and in part pointed out hereinafter.

In the drawings accompanying this specification and in which similar reference numerals refer to similar parts,

Figure 1 is a plan view of a drawing board constructed in accordance with the practice of the invention.

Figure 2 is an end view of the drawing board illustrating more particularly one form of plane-instrument guide for the board.

Figure 3 is a similar view showing a modified form of plane-instrument guide.

Figures 4 and 5 are transverse views taken through Figure 1 on the lines 4—4 and 5—5, respectively.

Figure 6 is a view similar to Figure 1 showing a modified form of the invention.

Figure 7 is an end view of the board shown in Figure 6 showing a shiftable straight edge for the board.

Figure 8 is an enlarged view of a portion of the board and straight edge shown in Figure 6 illustrating more particularly the manner in which the straight edge may be held in one of its limiting positions.

Figure 9 is a transverse view taken through Figure 8 on the line 9—9, and

Figure 10 is a perspective view of a detail.

Referring to the drawings, and at first more particularly to Figures 1 to 3 inclusive, 20 designates a drawing board of rectangular shape and 21 a plane working-surface having arranged thereon a work-sheet 22.

The board may be constructed of any suitable material possessing the quality of resistance to distortion under varying atmospheric conditions. It should be sufficiently strong to maintain a true

2

plane working surface under all conditions of use and is provided with means to serve as a straight edge for guiding plane instruments, as for example a triangle 23 shown in dot and dash lines in Figure 1. In one form such guide means consists of a strip 24 that seats against an edge of the board 20 and is fixedly secured thereto by suitable means, as for example nails 25.

The strip 24 is of less length than the board, 10 its ends terminating at equal distances from adjacent corners of the board, and has on its upper side projections 26 that are spaced with respect to each other and extend above the working-surface. In the form shown the width of the spaces between the projections 26 is coextensive with widths of the strip 24 and the projections 26 and the projections are of inverted V-shape and their inner surfaces 27 confronting the working surface of the board are in alignment with each other and with the edge of the board 20 to serve as guiding surfaces for the triangle. The sloping surfaces 28 of the projections 26 decline at a low angle and preferably extend to points slightly below the working surface so that the bottom surfaces 29 of the resulting depressions will lie below the working surface 21 and thus below the plane of movement of the triangle.

Owing to this arrangement, the plane-instruments will readily ride up over the projections 30 26 in inclined relation with the working surface, and may then be conveniently grasped for removing them from the board. In order to further assure that the triangle may be readily cammed up over the projections 26 the corners at the junctures of the sloping surfaces 28 and the guide surfaces 27 of said projections are removed. This may be accomplished by forming either a beveled surface at this point or, as indicated more particularly in Figure 4, a rounded surface 30 of such curvature that it will cause the triangle to veer from the working surface.

As will be readily understood, strips 24 may be arranged on each of the four edges of the board or, as shown in Figure 1, on adjacent sides of the board so that the guide surfaces 27 of adjacent strips will lie in planes mutually perpendicular to each other.

As an alternative form of guide or straight-edge for the plane-instruments, the board 20 may be provided with a plurality of separate plates

31 arranged at equally spaced intervals along an edge, or edges, of the board and secured thereto in the manner and with the means described in connection with the mode of securing the strips 24 to the board. The lower ends of the plates 5 may lie flush with the under-surface 32 of the board and the opposite ends of the plates are in the form of projections 33, preferably of triangular shape, that extend above the working surface 21 and have their inner surfaces 34 in alignment with each other to serve as a straight edge for a plane-instrument.

The sloping surfaces 35 of the projections 33, like those of the projections 26, also incline at a low angle and their inner corners are also removed to provide thereon the rounded surfaces 30. The end members of a row of plates 31 are spaced a suitable distance from the adjacent corner of the board 20, and on the upper surface of the board, between adjacent end plates or guide strips, are beveled surfaces 36 that slope downwardly from the working surface to support the corner portions of the work-sheet.

Suitable means are provided for holding the work-sheet immovable on the board. In the form illustrated, such means consist of resilient holders or clamping devices 37 that are initially in the form of a staple and have their legs 38 embedded in the edges of the board 20. The holders are of angular shape having their closed end or bar portions 39 overlying the legs 38 and in such relation thereto that when a bar 39 rests upon a beveled surface 36 the curved portions 40 at the juncture of the legs 38 with the body of a clamping device will be flexed in suitable degree to press the bar portion 39 firmly against the corners of the work-sheet. The spring portions 40 may, as illustrated, be of U-shape, or in the form of loops, if desired.

In spring devices 37 having two legs, as shown, said legs are driven diagonally into adjacent edges of the board and the bar 39 will then lie diagonally across the clamping surfaces 36. The bar 39 is, moreover, so positioned with respect to the base and the apex of a clamping surface 36 that it lies below the plane of the working surface and will, therefore, be well out of the path of movement of the drawing instruments on the work-sheet.

In the form of the invention shown in Figures 6 to 10 inclusive, certain of the plane-instrument guiding strips are seated slidably upon edges of the board in order that all portions of the guiding strips may be removed out of the plane of the working surface. One form that such a strip may assume in practice, and designated 41, is similar to the strip 24. It has the projections 26 on its upper edge and is of a length approximately equal to the distance between adjacent clamping surfaces 36. In a preferred form of the invention, the strip 41 is slidable in a plane normal to the working surface of the board and the distance of such movement is limited by pins 42 projecting from the edge of the board into slots 43 in the strip. The length of the slots determines the range of sliding movement of the strip, and their ends engage the pins 42 in the limiting positions of the strips. Thus, when the lower ends of the slots seat against the pins the projections will occupy their guiding positions, and when the opposite ends of the slots rest upon the pin the strip 41 will be in the fully depressed position wherein the projections 26 lie below the working surface and, therefore, out of the path of movement of the plane-instruments.

Convenient means are provided to hold the strip 41 in its limiting positions. To this end a plurality of spring clips 44, two in the present instance, are arranged at the edge of the board to press the strip 41 thereagainst. The spring clips have legs 45 to extend into the edge of the board and are bent to a suitable angle intermediate their ends to position the bar 46 for engagement with the side of the strip 41 and to flex the curved portion 47 at such angle in the degree required to hold the strip in frictional engagement with the board.

In order to further assure against the inadvertent shifting of the strip, said strip is provided with a pair of grooves 48 in its side to interlockingly engage the bar 46. The grooves 48 are so spaced with respect to each other that when the strip is in the instrument-guiding position the bar 46 will lie in one groove, and when the strip is depressed below the plane of the working surface the bar 46 will seat in the other groove 48.

In the form of spring member shown in Figures 6 to 9 inclusive, the spring portion 47 is shaped as a simple curve, or loop, but may be in the form of a helix 50, as shown more particularly in Figure 10.

As will be readily appreciated, shiftable strips 41 may be disposed on each of the four edges of a drawing board or only on certain edges and, if desired, one or more of the guide strips may be permanently attached to the board in the manner of the strip 24 at the upper edge of the board in Figure 6. The strips may, moreover, be of different form, as for example those designated 51, in Figures 6 to 8 inclusive, and have plane upper edges 52 and beveled surfaces 53 sloping gradually downwardly from the edges 52 to the ends of the strips for tilting the plane-instruments. The strips 51 are also shiftable up and down at the edge of the board and are held firmly thereagainst by the spring members 46.

I claim:

1. A drawing board having a plane working surface, and a plurality of relatively spaced projections arranged against one edge of the drawing board and jutting above the working surface and having surfaces in alignment with each other to guide a drawing instrument, the width of the spaces between the projections being coextensive with the width of said projections.

2. A drawing board having a plane working surface, a plurality of projections arranged in spaced relation with each other along and acting against the edge of the board and having surfaces in alignment with each other to guide a drawing instrument, the width of the spaces between the projections being coextensive with the width of said projections, and means for securing the projections to the edge of the drawing board.

3. A drawing board having a plane working surface, and a plurality of relatively spaced inverted V-shaped projections at an edge of the board projecting above the working surface, and surfaces on the projections in alignment with each other to guide a drawing instrument.

4. A drawing board having a plane working surface, a plurality of relatively spaced projections seating against one edge of the board and extending above the working surface, surfaces on the tops of the projections sloping downwardly in opposite directions, glide surfaces on the projections adjacent the working surface for guiding a drawing instrument, and cam surfaces on the projections at the junctures of the sloping surfaces with the glide surfaces.

5. A drawing board having a plane working surface, a plurality of relatively spaced projections seating against one edge of the board and extending above the working surface, guiding surfaces on the projections in alignment with each other for guiding a drawing instrument on the working surface, and beveled surfaces on the projections at the junctures of guiding surfaces with the upper surfaces of the projections to guide a drawing instrument over the projections during the sliding of such instrument from the working surface.
